OPERATING LEVER FOR AN ELECTRICAL SWITCH

Harry J. Collins, Jr., Bayside, and Alvin W. Krieger,
Milwaukee, Wis., assignors to Cutler-Hammer, Inc.,
Milwaukee, Wis., a corporation of Delaware

Filed Mar. 30, 1965, Ser. No. 84,521

Term of patent 14 years

(Cl. D26—13)

FIGURE 1 is an isometric view of an operating lever for an electrical switch showing our new design;

FIG. 2 is a side elevational view;

FIG. 3 is an end elevational view; and

FIG. 4 is a top view.

The portions shown in dotted lines are included for purposes of illustration only.

We claim:

The ornamental design for an operating lever for an electrical switch, substantially as shown and described.
